UNITED STATES PATENT OFFICE.

JOHN NELSON, OF GLASGOW, SCOTLAND.

PROCESS FOR THE CRACKING OF HYDROCARBON OILS AND THE LIKE.

1,391,569.

Specification of Letters Patent. Patented Sept. 20, 1921.

Application filed December 23, 1919. Serial No. 346,990.

To all whom it may concern:

Be it known that I, JOHN NELSON, a subject of the King of England, residing in Glasgow, Scotland, have invented certain new and useful Improvements in a Process for the Cracking of Hydrocarbon Oils and the like, of which the following is a specification.

This invention relates to the cracking of hydrocarbon oils and the like by those processes in which a liquid contact-substance, for example, a molten salt or a molten metal, is employed, and is particularly applicable in conjunction with the inventions forming the subject of my prior U. S. application, Serial Number 219,950, filed March 2nd 1918.

According to the present invention, the improved process for cracking hydrocarbon oils and the like comprises submitting the oil or its vapors to the action of a liquid contact-substance, and cooling the vapors prior to further treatment with the contact material. Preferably, the vapors are cooled to a temperature just above that of condensation before the succeeding cracking step. For many oils, the temperature throughout the process does not substantially exceed 620° C. and is preferably about 500°-550°, and the maximum cooling of the vapors between successive treatments is represented by a temperature of about 375°. The degree of cooling between successive steps need not be the same, but may be varied according to circumstances, for example, the extent to which the vapors have been already cracked.

It is preferred to effect the cracking of the oil in a series of steps, each step being of comparatively short duration. The temperature of the contact-substance may be the same for each period of contact, or a decreasing or increasing temperature may be employed. The contact material is kept agitated during the process as, for example, by the passage of the hydrocarbon. According to a modification of the invention, the oil or its vapors are submitted to the action of the liquid contact-substance in conjunction with steam.

If the oil to be cracked contains tarry or other objectionable products which cannot be eliminated during the cracking process, the oil may be distilled from an auxiliary vessel, and the distillate or vapors subjected to the cracking operation.

The contact material may be a molten metal, or alloy, for example, molten lead, or a fused salt, or mixture of salts, as sodium nitrate, or sodium hydroxid, but the invention is, of course, not restricted in respect to the use of a particular liquid contact-substance.

The extent of the cracking may be varied within certain limits by varying the depth at which the hydrocarbon or its vapors are delivered beneath the surface of the contact substance, and by the number of contact periods. As one object of the invention is to avoid production of much carbonaceous matter, it is material not to subject the oil or its vapors to the cracking temperature in constricted channels. The apparatus which forms the subject of my prior application affords special provision against this, as well as providing a means of operation of the process herein set forth.

The accompanying drawings show one form in sectional elevation of such apparatus set for the treatment of two different kinds of oil.

Figure 1 shows diagrammatically the arrangement when heavy oils of high boiling-point, such as petroleum fuel oils, are to be treated, and

Fig. 2 shows the setting for the treatment of lighter oils, such as coal-tar naphthas, boiling say, above 160° and under 240° C.

Fig. 3 shows a section through the furnace and cracking pot in a modified form the upper part of the pot being jacketed, as shown at H.

Referring to the drawings, A represents the heating chamber having four cracking-pots B, set in the flue C, of the furnace D. As shown, the arrangement is such that the chamber in which the pots are set is surrounded by the hot gases from the furnace. The flue C in which the cracking-pots are set may be divided above the level of the contact-substance in the pots with a transverse partition, as indicated by the chain lines in Fig. 1, to restrict the heating area in the pots. E is the inlet for the hydrocarbon, and F are the pipes which lead the vapors from one pot to the next. f—g represents the level of the molten contact-substance, g—h the zone of partial cooling, and h—i the cooling zone proper.

In Fig. 1, the flanges of the cracking-pots

are shown touching the crown G, of the furnace, the cooling area in this case being merely that derived from the depth of the furnace crown added to the height above 5 the latter of the pipe, and, to a lesser degree, to the distance from the crown to the surface of the contact-substance. The figure illustrates, therefore, the minimum degree of intermediate cooling for heavy hydro- 10 carbon vapors between successive stages of treatment.

In the case of lighter oils, such as the coal-tar naphthas mentioned, the flanges of the cracking-pots are not flush with the 15 furnace-crown setting, but extend out of the furnace as shown in Fig. 2. In the case of petroleum solar-oil, a similar variation would be made in order to secure the maximum cracking results. It is, of course, to 20 be understood that there is necessarily a limit beyond which the communicating pipes between the cracking pots project beyond the sphere of heat, and the distance must never be so great that condensation to liquid 25 of the hydrocarbon vapors can take place between successive treatments. The cooling is preferably the maximum possible in order to obtain the greatest temperature difference between the vapor and the contact-substance. 30 The selection of the particular contact-substance to be used depends, among other considerations, upon the working temperature employed. In operating at moderate temperatures (such as are utilized in the 35 production of volatile spirits for use in petrol engines) it is preferred to make use of a bath of molten lead or of salts of suitable melting point, and to pass the hydrocarbon or its vapors into the bath at a suitable 40 distance below its surface. If temperatures exceeding those at which lead can be satisfactorily employed are required, metals or alloys of higher melting point than lead may, of course, be used.

45 It has been found that if oil be cracked by the aid of a liquid contact-substance in a series of successive steps, each step being of comparatively short duration, and the oil vapors be subjected to a cooling action 50 prior to treatment in one or more further steps, a much more satisfactory conversion of the oil can be obtained than has hitherto been the case. It is to be understood, however, that the total period of contact between 55 the oil and the contact-substance is not necessarily short; it may be prolonged as desired to secure the maximum degree of conversion under the particular conditions of working; it is each step of contact which is short.

60 As the time during which the hydrocarbon and its product remain in contact with the hot liquid substance is brief, the whole product or any desired fraction thereof, may be subjected to one or more re-treatments;

for example the heavier fraction, condensed 65 of the hot vapors by means of a dephlegmator in the known manner, may be thus re-treated.

What I claim as my invention and desire to secure by Letters Patent is:—

70 1. The herein described process for cracking hydrocarbon oils and the like which comprises introducing the hydrocarbon into a liquid contact substance in a series of steps and between two successive steps cooling the 75 vapors to a point just above that at which they condense.

2. The herein described process for cracking hydrocarbon oils and the like which comprises introducing the hydrocarbon into a liquid metallic contact substance in a series of steps and between two successive steps cooling the vapors to a point just above that 80 at which they condense.

85 3. The herein described process for cracking hydrocarbon oils and the like which comprises introducing the hydrocarbon and steam into a liquid contact substance in a series of steps and between two successive steps cooling the vapors to a point just above 90 that at which they condense.

4. The herein described process for cracking hydrocarbon oils and the like which comprises introducing the hydrocarbon into a liquid contact substance in a series of steps 95 of brief contact period and between two successive steps cooling the vapors to a point just above that at which they condense.

5. The herein described process for cracking hydrocarbon oils and the like which comprises introducing the hydrocarbon into a liquid contact substance at a temperature of 100 500°-550° in a series of steps and between two successive steps cooling the vapors to a point just above that at which they condense.

10 6. The herein described process for cracking hydrocarbon oils and the like which comprises introducing the hydrocarbon into a liquid contact substance at a temperature 110 not exceeding 620° in a series of steps and between two successive steps cooling the vapors to a temperature not substantially below 375° C.

115 7. The herein described process for cracking hydrocarbon oils and the like which comprises introducing the hydrocarbon into a liquid metallic contact substance at a temperature of 500°-550° in a series of steps and between two successive steps cooling the 120 vapors to a point just above that at which they condense.

125 8. The herein described process for cracking hydrocarbon oils and the like which comprises introducing the hydrocarbon into a liquid metallic contact substance at a temperature not exceeding 620° in a series of steps and between two successive steps cool-

ing the vapors to a temperature not substantially below 375° C.

9. The herein described process for cracking hydrocarbon oils and the like which comprises introducing the hydrocarbon into a liquid contact substance in a series of steps and between two successive steps cooling the

vapors of the hydrocarbon to a point just above that at which they condense, and varying the temperature of the contact substance 10 at different steps.

In testimony whereof I affix my signature.

JNO. NELSON.
